(57) **CLAIM**

We claim the ornamental design for a tactile user interface device, as shown and described.

DESCRIPTION

FIG. 1 is an isometric view from the top, front, right of a tactile user interface device showing our new design.

FIG. 2 is an isometric view from the bottom, back, left thereof.

FIG. 3 is a plan view from the left thereof.

FIG. 4 is a plan view from the right thereof.

FIG. 5 is an elevation view from the front thereof.

FIG. 6 is an elevation view from the back thereof.

FIG. 7 is an elevation view from the top thereof; and,

FIG. 8 is an elevation view from the bottom thereof.

The broken lines depict portions of the tactile user interface device that form no part of the claimed design.
